BOAT SPEEDOMETER

Filed May 24, 1946

UNITED STATES PATENT OFFICE

2,449,590

BOAT SPEEDOMETER

Roger C. Colpaert, Detroit, Mich.

Application May 24, 1946, Serial No. 672,126

2 Claims. (Cl. 73—186)

1

My invention relates to an improved speedometer for watercraft, and the primary object of my invention is to provide a novel electro-mechanical device of this character which is operated by the pressure of the water against a spring-balanced plunger upon forward motion of the craft, and is combined with electrical means for calibrating the amount of movement of the plunger and showing the results in terms of miles per hour.

Another important object of my invention is to provide a simple and reliable speedometer of small size and compact design which is relatively inexpensive and is easily installed.

Other important objects and advantages of my invention will be apparent from the following description and the accompanying drawings, wherein for purposes of illustration only, a preferred embodiment is set forth in detail.

In the drawings:

Figure 1 is a general vertical longitudinal central section taken through Figure 2 on the line 1—1, and showing installation thereof in the bottom of a boat.

Figure 2 is a horizontal section taken on the line 2—2 of Figure 1.

Figure 3 is a top plan view of the rheostat with the cover removed.

Figure 4 is a top plan view of the electrical indicator or speedometer dial and mechanism.

Figure 5 is a wiring diagram of the electrical connections.

Referring to the drawings in detail, the numeral 6 generally designates the body of the water speedometer, which comprises the horizontal cigar-shaped lower part 7 composed of the lower section 8 and the upper section 9, joined along the horizontal line 10, and preferably formed of bronze castings. The upper section 9 has rising centrally therefrom the elongated thin section strut 11, which includes at its upper end a forwardly and rearwardly enlarged portion 12 having a flat top 13 for engaging a gasket 14 pressed against the bottom plate 15 of a boat (not shown).

Rising from the strut portion 12 intermediate its ends is a tubular portion 16 which has on its upper end the speedometer dial mechanism, which is generally designated 17, hereinafter described in detail.

The tubular part 16 is threaded at 18 above the boat bottom 15 for a nut 19 which is to be threaded downwardly thereon against a washer 20 which in turn presses on a gasket or packing ring 21 engaging the upper side of the boat bottom 15

2

around the hole 22 which passes said tubular portion 16, whereby the device is securely installed in water-tight manner.

The bore 23 of the tubular portion 16 continues 5 downwardly through the strut portion 11 and upper body section 9 to open into the top of a longitudinal elongated generally rectangular chamber 24 formed in the bottom of said upper section and closed on the lower side by the top of 10 the lower section 8. Aligned slide bores 25 and 26 are formed through the front and rear ends of the upper body section 9 which open into corresponding ends of the chamber 24.

A horizontal rectangular frame 27 having rack 15 teeth 28 along one side thereof is located in the chamber 24 and has attached to its opposite ends the rods 29 and 30, respectively, which slide in the bores 25 and 26, respectively. The rear end of the bore 26 is closed by a threaded plug 31 20 which acts as an abutment for the adjacent end of a helical expanding spring 32 positioned in the bore 31 with its opposite end engaging the slide rod 30. The front slide rod 29 has a flat pressure head 33 on the forward end.

25 Meshed with the rack teeth 28 on the frame 27 is a pinion 34 on a rotary shaft 35 pivoted at its lower end in a socket 36 formed in the lower body section 8 and journaled at its upper end in an opening 37 in a plate 38.

30 The said plate 38 forms the bottom of a circular pan-shaped rheostat mechanism casing 39 which has an insulated rheostat resistance element 40 arranged around the inner side of its side wall, as indicated in Figure 3. A spring-pressed wiper 35 contact 41 is fixedly mounted on the upper end of the shaft 35 with its contact or brush 42 engaging the resistance element 40. A casing collar 39' fits on the top of the tubular portion 16 and is secured by screws 40'.

40 It is obvious from the foregoing that the balancing spring 32 keeps the forward rod 29 in its forwardmost position when the boat is not moving forward or is not standing in a rearwardly flowing stream, and that, as the boat moves forward the pressure of the water on the head 33 will

45 push the rod 29 rearwardly an amount corresponding to the magnitude of the water pressure and that this operates through the rack teeth 28 and pinion 34 to turn the shaft 35 and change the 50 position of the brush 42 on the rheostat element 40, thereby correspondingly varying the resistance of any electrical circuit in which the rheostat may be incorporated.

This variation in electrical resistance is here 55 used to vary the magnetization of a solenoid coil

43 having a core 44 pivoted at one end at 45 to an arm 46 on a sector gear 47 pivotally supported at 48 in a speedometer dial casing 49. The sector gear 47 is meshed with a pinion 50 including a needle or pointer 51 pivoted on the casing 49, with a contractible spring 53 stretched between a part of said casing and one side of the sector gear 47 to initially position the pointer 51 at "zero" on the miles-per-hour concentric dial 53, and return it to "zero" after operation around the dial.

It is clear that the amount of energization of the solenoid coil 43 is determined by the travel of the rheostat contact 42 on the rheostat element 40 away from its starting position in response to the water pressure on the head 33, and that the amount of energization or magnetization of the solenoid coil determines the position of the pointer 51 relative to the dial 53 to accurately show the forward rate of speed of the boat in still water.

The speedometer dial mechanism casing 17 may be mounted on any suitable place in the boat and have the necessary wires 54 and 55 (see Fig. 5) led thereto, with a hand switch 56 and a battery 57 connected in the wire 54.

I claim:

1. A speedometer for a boat having a bottom panel comprising a streamlined body adapted to be positioned in the water beneath said panel in fore and aft manner and having a reduced portion adapted to rise through and be sealed in an opening formed in said panel into the interior of the boat, a forwardly spring-pressed plunger working horizontally in said body, said plunger having a water pressure head against which the water presses on forward motion of the boat to move said plunger rearwardly an amount corresponding to the forward speed of the boat, a vertical rotary shaft extending through said reduced portion and into said body, means operatively connecting said shaft and plunger to turn said shaft in opposite directions in accordance with the position and movement of said plunger, a lateral rheostat contact fixed on the upper part

of said shaft, a circular rheostat resistance element supported on the upper part of said reduced portion for engagement by said contact.

2. A speedometer for a boat having a bottom panel comprising a streamlined body adapted to be positioned in the water beneath said panel in fore and aft manner and having a reduced portion adapted to rise through and be sealed in an opening formed in said panel into the interior of the boat, a forwardly spring-pressed plunger working horizontally in said body, said plunger having a water pressure head against which the water presses on forward motion of the boat to move said plunger rearwardly an amount corresponding to the forward speed of the boat, a vertical rotary shaft extending through said reduced portion and into said body, means operatively connecting said shaft and plunger to turn said shaft in opposite directions in accordance with the position and movement of said plunger, a lateral rheostat contact fixed on the upper part of said shaft, a circular rheostat resistance element supported on the upper part of said reduced portion for engagement by said contact, and electro-mechanical speed-indicating means effectively connected in circuit with said rheostat contact and rheostat resistance element.

ROGER C. COLPAERT.
